UNITED STATES PATENT OFFICE.

RUDOLF E. HELLMUND, OF SWISSVALE, AND BENJAMIN S. MOORE, OF WILKINSBURG, PENNSYLVANIA, ASSIGNORS TO WESTINGHOUSE ELECTRIC & MANUFACTURING COMPANY, A CORPORATION OF PENNSYLVANIA.

ARRANGEMENT OF LEADS FOR DYNAMO-ELECTRIC MACHINES.

1,351,907.

Specification of Letters Patent.

Patented Sept. 7, 1920.

Application filed July 5, 1917. Serial No. 178,600.

To all whom it may concern:

Be it known that we, RUDOLF E. HELLMUND, a subject of the Emperor of Germany, and a resident of Swissvale, in the county of Allegheny and State of Pennsylvania, and BENJAMIN S. MOORE, a citizen of the United States, and a resident of Wilkinsburg, in the county of Allegheny and State of Pennsylvania, have invented a new and useful Improvement in Arrangement of Leads for Dynamo-Electric Machines, of which the following is a specification.

Our invention relates to an arrangement of collector leads for the rotatable members of dynamo-electric machines and it has for its object to provide novel means for preventing displacement and chafing of the leads under the influence of centrifugal force during the operation of the machine.

It has heretofore been proposed to locate collector leads within the shaft of a rotatable member but considerable difficulty has been encountered in properly supporting the portions of the leads that extend between the outer surface of the shaft and the windings to which the leads are connected. It has also been found that the vibration of the leads within the shaft causes injury to the insulation thereof.

According to our present invention, we provide means for spacing apart and individually supporting each lead at the point where it leaves the shaft and further means for protecting the exposed portions of the leads against injury. We also propose to embed the portions of the leads that are located within the shaft in a solid mass of insulating material.

In the accompanying drawings, Figure 1 is a transverse sectional view of a portion of the rotating member of a dynamo-electric machine embodying our invention; Figs. 2 to 5, inclusive, are fragmentary views, respectively, showing details of the means for supporting and protecting the collector leads.

Referring to Fig. 1, a magnetizable core member 1 is mounted on a spider 2 that is carried by a shaft 3 and is adapted to rotate therewith. The shaft 3 is provided with a centrally located longitudinally extending opening 4 and passages 5 extending at an angle thereto. The spider 2 is provided with passages 6 that register with the pas-

sages 5 and terminate at a point adjacent to the end of the core member 1. A plurality of collector leads 7 extend through the opening 4 and the passages 5 and 6, respectively, and project beyond the spider 2 to a point below the overhanging end portions of the winding 8 that is carried by the core member 1.

The portions of the leads 7 that are located within the opening 4 are embedded in a mass of insulating material 9 that is surrounded by a tube 10 which is preferably composed of tough and fibrous insulating material. In applying the insulating material 9 to the leads 7, the tube 10 is first slipped over the leads 7, with the portions that are to be located within the passages 5 and 6 projecting beyond the ends of the tube 10. Insulating material 9, preferably in the form of bakelite or other similar material in a powdered or fusible condition is then placed in the tube 10 until it fills all the space between the leads and it is changed into a compact mass by the application of heat and pressure. The projecting portions of the leads 7 are then pulled through the opening 4 and the passages 5 and 6 until the end of the tube 10 reaches the end of the opening 4. We prefer that the tube 10 shall fit rather loosely within the opening 4 so that torsional stresses within the shaft 3 will not be transmitted to the mass of insulating material 10.

The portions of the leads 7 that project beyond the end of the spider 2 are spaced apart and supported by a member 11. As best shown in Figs. 3 and 4, the member 11 comprises a plurality of spaced fingers 12 to which the leads 7 are respectively secured by means of banding 13. The member 11 further comprises supporting lugs 14 that are secured to the spider 2 by means of studs 15 in threaded engagement with openings 16 that are provided in the spider, as best shown in Fig. 2. The leads 7 are respectively connected to the end connections 17 of the winding 8 by terminal members 18. The projecting portions of the leads 7 are protected by a shield member 19 that comprises a U-shaped portion 20 that embraces the leads 7 and is provided with oppositely disposed wing portions 21 that are secured to the spider 2 by means of nuts 22 coating with the studs 15. The

shield 19 further comprises an inclined portion 23 and a portion 24 that is substantially parallel to the top of the portion 20 and is secured to the end-turn supporting member 25.

From the foregoing, it is apparent that the portions of the leads located within the shaft are prevented from vibrating and chafing against each other because of the solid mass of insulating material surrounding the same and that the portions of the leads projecting beyond the spider are properly spaced apart and supported, and while we have shown our invention in its simplest and preferred form, it is not so limited but is susceptible of various minor changes and modifications within the scope of the appended claims.

We claim as our invention:

- 20 1. In a dynamo-electric machine, the combination with a shaft, a core mounted thereon and a winding carried by the core, of leads for the winding extending through the shaft and projecting beyond the core and means for individually supporting the leads beyond the core, said means comprising arms to which said leads are attached.
- 25 2. In a dynamo-electric machine, the combination with a shaft, a core mounted thereon and a winding carried by the core, of a plurality of leads for the winding extending through the shaft and projecting beyond the core and means for spacing apart and individually supporting the leads beyond the core, said means comprising a plurality of arms disposed at an angle to each other to which said leads are attached.
- 30 3. In a dynamo-electric machine, the combination with a shaft, a spider provided with openings therein mounted on said shaft, a core carried by the spider and pro-

vided with a winding having over-hanging end portions, of a plurality of leads for the winding extending through the shaft and openings in the spider and projecting beyond the end of the core and means mounted at the end of said openings for individually supporting the leads beyond the core and below the end portions.

4. In a dynamo-electric machine, the combination with a shaft, a spider mounted on a core carried by the spider and provided with a winding having overhanging end portions, of a plurality of leads for the winding extending through the shaft and the spider and projecting beyond the end of the core, and a member carried by the spider for individually supporting each of the leads, said member comprising a plurality of arms disposed at an angle to each other and extending parallel to said leads, and means for binding said leads to said arms.

5. In a dynamo-electric machine, the combination with a shaft, a spider mounted thereon and provided with openings therein, a core carried by the spider and provided with a winding having overhanging end portions, of a plurality of leads for the winding extending through the shaft and openings in the spider and projecting beyond the end of the core, and supporting members for the leads mounted at the ends of said openings and comprising a plurality of arms disposed at an angle to each other and extending parallel to said leads and means comprising stranded insulating material for binding said leads to said arms.

In testimony whereof, we have hereunto subscribed our names this 28th day of June, 1917.

RUDOLF E. HELLMUND.
BENJAMIN S. MOORE.
